Primary Examiner — Mary Ann Calabrese*Assistant Examiner* — Katelin G Kloberg(74) *Attorney, Agent, or Firm* — Alan G. Towner(57) **CLAIM**

The ornamental design for a display case for coatings, as shown and described.

DESCRIPTION

FIG. 1 is a top and front isometric view of a display case for coatings, showing our new design;

FIG. 2 is a bottom and front isometric view thereof;

FIG. 3 is a front view thereof;

FIG. 4 is a left side view thereof;

FIG. 5 is a right side view thereof;

FIG. 6 is a back view thereof;

FIG. 7 is a top view thereof; and,

FIG. 8 is a bottom view thereof.

The broken lines depict portions of the display case for coatings and form no part of the claimed design.
